UNITED STATES PATENT OFFICE.

GENSUKE YOSHIDA, OF NEW YORK, N. Y., ASSIGNOR TO GINNUOSUKE NAKAYAMA, OF NEW YORK, N. Y.

DESIGN FOR A COMBINED LAMP STAND AND INCENSE BURNER.

Application filed September 22, 1923. Serial No. 7,291. Term of patent 3½ years.

To all whom it may concern:

Be it known that I, GENSUKE YOSHIDA, a subject of the Emperor of Japan, and a resident of the city of New York, borough of Manhattan, in the county and State of New York, have invented a new, original, and ornamental Design for a Combined Lamp Stand and Incense Burner, of which the following is a specification, reference being had to the accompanying drawing, forming part thereof.

The figure is a perspective view of a combined lamp stand and incense burner, showing my new design.

I claim:

The ornamental design for a combined lamp stand and incense burner, as shown.

GENSUKE YOSHIDA.
